(57) **CLAIM**

The ornamental design for an electric folding bed, as shown and described.

DESCRIPTION

FIG. 1 is a perspective view of the electric folding bed showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, but with the bed shown in a partially folded position, and with the legs and leg supports shown removed.
